UNITED STATES PATENT OFFICE.

WILLIAM H. SMITH, OF NEW HAVEN, CONNECTICUT.

GARTER.

1,379,787.

Specification of Letters Patent. Patented May 31, 1921.

Application filed February 18, 1921. Serial No. 446,007.

To all whom it may concern:

Be it known that I, WILLIAM H. SMITH, a citizen of the United States, residing at New Haven, in the county of New Haven and State of Connecticut, have invented a new and useful Improvement in Garters; and I do hereby declare the following, when taken in connection with the accompanying drawings and the characters of reference marked thereon, to be a full, clear, and exact description of the same, and which said drawings constitute part of this application, and represent, in—

Figure 1, a plan view of a garter constructed in accordance with my invention;

Fig. 2, a view showing the device as in use.

This invention relates to improvements in garters, and particularly in garters for men's use, the object of the invention being a simple construction which can be made at a very low cost of manufacture and which will be as effective as those more expensive, and the invention consists in the construction as hereinafter described and particularly recited in the claims.

In carrying out my invention I employ an elastic cord 5, to one end of which I attach a hose-supporting clasp 6 of any approved construction. The opposite end of the cord is formed with a loop 7. Upon the cord, between its ends, is a button 8, through the eyes of which the cord is passed, so that the button has a firm bite upon the cord but

may be readily adjusted thereon. In use, 35 the clasp 6 is connected with the top of the stocking in the usual way, the cord passed around the leg and the loop end folded around the cord, between the clasp and the button, and the loop-end returned and the 40 loop engaged with the button, as shown in Fig. 2 of the drawings. The button may be adjusted to adapt the device for the wearer, and may be adjusted as occasion may require to take up for stretching. The device may 45 be produced at very low cost for manufacture and is effective in use.

I claim:

1. A garter comprising an elastic cord formed with a loop at one end and provided 50 with a hose-supporting clasp at the opposite end, and a button mounted on the cord between its ends.

2. A garter comprising an elastic cord formed with a loop at one end and provided 55 with a hose-supporting clasp at the opposite end, and a button on the cord between its ends and provided with eyes through which the cord is passed so that the button has a bite upon the cord. 60

In testimony whereof, I have signed this specification in the presence of two subscribing witnesses.

WILLIAM H. SMITH.

Witnesses:

FREDERIC C. EARLE,
MALCOLM P. NICHOLS.
